ROLLER SKATE HAVING DETACHABLE
ROLLER ASSEMBLY

Earl Van Horn, Mineola, N. Y.

Application July 6, 1950, Serial No. 172,247

10 Claims. (Cl. 280—11.28)

1

This invention relates to improvements in roller skates of the type shown in my Patent Numbers 2,558,696 and 2,578,961, the applications for which were copending herewith which are now known in the art as "double-action kingpin skates" because there are flexible connections between both ends of the kingpins and adjacent parts of the skate.

In developing skates of this type I have invented certain novel features which are disclosed herein, for which I desire patent protection. These features, which are defined in claims, include the design of a one-piece hanger bracket, which may be stamped out of sheet metal, shaped to form a longitudinally elongated pocket for receiving a resilient pressure member surrounding the kingpin, a surface for supporting a head at the upper end of the kingpin and a receptacle for supporting a socket insert for receiving the upper end of the track arm.

A pair of these hanger brackets may be differently spaced apart longitudinally to correspond to skates of different sizes and then interconnected by bridging pieces, channel-shaped in cross section, cut to desired lengths and welded to the spaced hanger brackets before the assembly is affixed to the footplate.

A further disclosure herein is that of a novel construction whereby the roller assemblies may be attached to and removed from the hanger brackets from the under side of the footplate without removing the skate from the shoe to which it is attached.

Referring to the drawings,

Fig. 1 is a plan view of a skate which is made according to and embodies my invention, with parts of the footplate broken away to show the construction of parts under it;

Fig. 2 is a side elevation, partly in section, of the skate shown in Fig. 1. The section of this figure is taken on the line 2—2 of Fig. 1;

Fig. 3 is a front elevation of the parts shown in the preceding figures.

In Figs. 1-3 a toeplate or brake is shown in dotted lines. This of itself forms no part of the present invention, but one of the truck arms shown in these figures is especially designed to receive such toeplate. This feature and the toeplate are more fully described in my copending application Serial No. 252,873, filed October 24, 1951.

Fig. 4 is a sectional front elevation on an enlarged scale of the upper part of a kingpin and adjacent parts.

Fig. 5 is a sectional side elevation of a bridge-

2

piece like that shown in Fig. 2, but of shorter length, together with parts of two hanger brackets to which the bridge-piece is connected.

Fig. 6 is a perspective view, partly in section, of some of the parts shown in Fig. 4, with the retainer removed from its kingpin head holding position.

Fig. 7 is a transverse sectional elevation on an enlarged scale of some of the parts. This section is taken on the line 7—7 of Fig. 2.

Fig. 8 is a plan view of a skate, with its footplate tilted in one direction; and

Fig. 9 is a front elevation of the parts shown in Fig. 8. Figs. 8 and 9 are more or less diagrammatic and illustrate the operation of the invention.

A designates a footplate, which may be secured to a skater's shoe. Two wheel assemblies B, C are below the plate. These are of similar construction but are placed oppositely. Each of them comprises a one-piece hanger bracket 18 stamped out of sheet metal, having parallel longitudinal walls 11. The lower edges 12 of the walls 11 are inclined at an angle to the footplate A. These walls 11 form longitudinal edges of a rectangular pocket. The lateral ends of this pocket are designated by 13, 13A. As shown in Fig. 2, the lower parts of the side walls 11 are bent upwardly over the edges 12 and then inwardly and across from wall to wall to form a flat plate 14 parallel with the lower edges 12, in the center of which is an orifice 15. The upper parts of the hanger are bent to form outwardly extending flanges 16, by means of which the hanger may be affixed to the footplate by rivets 17.

The hanger bracket also forms another flat plate 18 at one of its ends inclined to the footplate in the opposite direction from the inclination of the plate 14. In it is an orifice 19 longitudinally spaced from the orifice 15. This orifice is formed with an upwardly extending annular portion 19A, into which is forced a socket insert 20 (Fig. 2).

At its other end a part of the hanger bracket extends beyond the wall 13, as shown at 21, and has upstanding parallel sides 22, as shown in Figs. 2 and 7.

The socket insert 20 has an annular flange 25 and inner and outer frusto-conical surfaces 26, 27. The inner surface is closed at its upper end by a semi-circular surface 28. This socket member is forced into the orifice 19 until its flange 25 abuts the plate 18. Its outer surface then engages the annular portion 19A. The socket in-

sert is thereby permanently affixed to the hanger bracket.

30 is a kingpin. At its upper end is a head 31, the under side 32 of which is flat. Below the head is an externally threaded shank portion 33. A part of the head and of the adjacent part of the shank portion are cut away to form parallel sides 34, 35 normal to the under side 32 of the head. The distance between these sides is less than the diameter of the shank portion 33. The lower part 36 of the kingpin is an externally threaded shank portion of less diameter than that of the portion 33.

40 is an axle bracket, in which the axle 41 is supported. 42 designates the rollers on the axle. 43 is an arm which projects from the axle in a direction substantially parallel the edges 22 of the hanger bracket. 44 designates an orifice in this projecting arm. 45 is a truck arm, in the upper end of which is a pin 46 having a flange 47 intermediate its length. The lower part of this pin fits tightly into the truck arm. Its upper portion extends into the socket insert and terminates in a semi-circular surface 48, which, when the parts are in the positions shown in the drawings, abuts the surface 23 of the socket insert.

I will now describe how the parts thus pointed out are put together: The head 31 of the kingpin is passed through the orifice 15 in the plate 14. Then, a flat retainer 59 is moved longitudinally on the upper surface of the plate 14 into a position between this upper surface and the under side 32 of the kingpin. The retainer has parallel arms 51, 52 separated by a slot 53 of a width which affords a clearance for the sides 34, 35 of the kingpin. The ends 51A, 52A of these arms turn upwardly, as shown, back of the head 31. 54 is an arm extending from the other end of the retainer, having an upturned end 54A by which the retainer may be removed.

When the parts are positioned as shown in Fig. 2, a rectangular pressure member 60 is placed around the kingpin and moved up into the pocket formed by the longitudinal sides 11 and the transverse sides 13, 13A of the hanger bracket. Then, a flanged plate 61, which also surrounds the kingpin and is of a shape similar to that of the pocket formed in the hanger bracket, is moved up against the under side of the resilient pressure member 63. Indentations 62 are formed in this plate. 63 is a nut in threaded engagement with the threaded shank portion 33 of the kingpin. A projection 64 on the upper surface of this nut cooperates with one of the indentations 62 to lock the nut in place. By turning the nut upwardly a desired amount of pressure is imposed upon the pressure member 60, which tends to keep the kingpin in a vertical longitudinal plane through the longitudinal axis of the footplate A.

A universal joint connection is thus formed between the upper part of the kingpin and the hanger bracket as the flat surface of the head is able to rock on the retainer 59 to allow the lower part of the kingpin to move in all directions. This movement is opposed by the pressure member 60 to an extent proportional to the pressure imposed upon it by the nut 63, and this pressure tends to return the kingpin to its normal position after it has been deflected therefrom.

Another nut 65 in threaded engagement with the portion 33 of the kingpin engages a flanged washer 66 surrounding the kingpin and provided with indentations 67, with which a projection 68 on the nut 65 engages with one of the indentations 67 to lock the parts in desired positions.

Between the washer 66 and the arm 43 of the axle bracket is another resilient pressure member 69. The pressure on this member can be adjusted by turning the nut 65. The engagement of the arms 51, 52 of the retainer with the flat sides 34, 35 of the kingpin prevents rotation of the kingpin while these adjustments are being made.

The lower portion of the kingpin projects through an insert 49 in the orifice 44. A castellated nut 37, in threaded engagement with the lower portion 36 of the kingpin, abuts on the lower surface of the insert 49. This nut is capable of rocking on the insert 49 and thus forms a universal joint connection between the lower part of the kingpin and the axle bracket. The pressure member 69 opposes this rocking movement and tends to bring the arm 43 of the axle bracket into alignment with the longitudinal axis of the footplate after such a rocking movement has been effected. The opposition to this rocking movement, and the amount of pressure effective to return the parts to their normal positions, depends upon the amount of pressure exerted by the member 69, which can be adjusted by turning the nut 65.

The parts thus described are those of the wheel assembly on the rear end of the skate. The wheel assembly at the other end of the skate is similar, but in this particular case a part 70 of the truck arm is shown, which may be provided for the purpose of receiving a toeplate or brake 71, if desired.

The wheel assemblies are mounted on the footplate A in opposite directions, with the ends of their extensions abutting each other. These extensions are cut to different lengths, according to the length of the footplates, to which the hanger brackets are to be applied. 80 is a channel-shaped bridgepiece having upturned sides 81 spaced within and affixed to the extensions 21. The extensions 21 and the bridgepiece 80A in Fig. 5 are shorter than similar parts in Fig. 2 and this illustrates the fact that these parts are of different lengths to accommodate skates with footplates of different lengths.

When the king pins are tilted out of the vertical plane, as diametrically shown at 30A in Fig. 9, it will shift the axles to the positions shown at 41A, 41B in Fig. 8. This operation is similar to the usual one, with the exception of the fact that, because of the flexible connection between the footplate and the upper ends of the kingpins, the action of the kingpin on the axle bracket is not positive, but is cushioned to the extent determined by the amount of pressure exerted upon the upper resilient pressure members 60, which have a tendency to maintain the kingpin in a vertical position.

Because of the adjustability of the degree of pressure on the members 60 and 69, these parts may be regulated to suit the individual user's tastes and requirements. It has been pointed out that these adjustments can be made independently and the parts locked in the desired positions.

Because of the elongated shape of the upper resilient members 60, they will oppose longitudinal movement of the lower ends of the kingpins to a greater extent than they will oppose the lateral movement of the lower ends of the kingpins.

Various modifications in construction, mode of operation, method and use of an invention may and do occur to others, especially after benefiting from knowledge of such disclosures

as that herein presented of the principles involved, but the invention itself is not confined to the present showing.

I claim:

1. In a skate, a footplate, a hanger thereon having a plate spaced from the footplate, a roller assembly comprising an axle, an axle bracket having an arm extending longitudinally from the axle and a truck arm extending upwardly from the axle, means for connecting the upper part of the truck arm with the footplate, a kingpin passing through an orifice formed in said longitudinally extending arm of the axle bracket and having a head passing through an orifice formed in said plate of the hanger, said second orifice being longitudinally spaced from the connection of the truck arm with the footplate, said kingpin head being above the plate of the hanger, a removable retainer interposed between said head and the plate of the hanger, a pressure member interposed between the longitudinally extending arm of the axle bracket and the hanger, and a nut under said longitudinally extending arm in threaded engagement with the kingpin.

2. In a skate, a footplate, a hanger thereon having a plate spaced from the footplate, a roller assembly comprising an axle, an axle bracket having an arm extending longitudinally from the axle and a truck arm extending upwardly from the axle, means for flexibly connecting the upper part of the truck arm with the footplate, a kingpin passing with clearance through an orifice formed in said longitudinally extending arm of the axle bracket and having a head passing through an orifice formed in said plate of the hanger, said second orifice being longitudinally spaced from the connection of the truck arm with the footplate, said kingpin head being above the plate of the hanger, a removable retainer interposed between said head and the plate of the hanger, a resilient pressure member interposed between the longitudinally extending arm of the axle bracket and the hanger, and a nut under said longitudinally extending arm in threaded engagement with the kingpin.

3. In a skate, a footplate, a hanger thereon having a plate disposed at an angle to and spaced from the footplate, a roller assembly comprising an axle, an axle bracket having an arm extending longitudinally from the axle and a truck arm extending upwardly from the axle, means for flexibly connecting the upper part of the truck arm with the hanger, a kingpin passing with clearance through an orifice formed in said longitudinally extending arm of the axle bracket and having a head passing through an orifice formed in said plate of the hanger, said second orifice being longitudinally spaced from the connection of the truck arm with the hanger, said kingpin head being above the plate of the hanger, a removable retainer interposed between said head and the plate of the hanger, a resilient pressure member interposed between the longitudinally extending arm of the axle bracket and the hanger, and a nut under said longitudinally extending arm in threaded engagement with the kingpin.

4. In a skate, a footplate, a hanger thereon having a plate spaced from the footplate, a roller assembly comprising an axle, an axle bracket having an arm extending longitudinally from the axle and a truck arm extending upwardly from the axle, means for connecting the upper part of the truck arm with the footplate, a king-

pin passing through an orifice formed in said longitudinally extending arm of the axle bracket and having a head passing through an orifice formed in said plate of the hanger, said second orifice being longitudinally spaced from the connection of the truck arm with the footplate, said kingpin head being above the plate of the hanger, a removable retainer interposed between said head and the plate of the hanger, an adjustable pressure member surrounding the kingpin interposed between the longitudinally extending arm of the axle bracket and the hanger, and a nut under said longitudinally extending arm in threaded engagement with the kingpin.

5. In a skate, a footplate, a hanger thereon having a plate spaced from the footplate, a roller assembly comprising an axle, an axle bracket having an arm extending longitudinally from the axle and a truck arm extending upwardly from the axle, means for connecting the upper part of the truck arm with the footplate, a kingpin passing through an orifice formed in said longitudinally extending arm of the axle bracket and having a head passing through an orifice formed in said plate of the hanger, said second orifice being longitudinally spaced from the connection of the truck arm with the footplate, said kingpin head being above the plate of the hanger and having flattened parallel sides under the head laterally spaced apart a distance less than the lateral dimension of the head, a removable retainer interposed between said head and the plate of the hanger, said retainer having arms spaced to pass the flattened sides of the kingpin with clearance, a pressure member interposed between the longitudinally extending arm of the axle bracket and the hanger, and a nut under said longitudinally extending arm in threaded engagement with the kingpin.

6. In a skate, a footplate, a hanger thereon having a plate spaced from the footplate, a roller assembly comprising an axle, an axle bracket having an arm extending longitudinally from the axle and a truck arm extending upwardly from the axle, means for connecting the upper part of the truck arm with the footplate, a kingpin passing through an orifice formed in said longitudinally extending arm of the axle bracket and having a head passing through an orifice formed in said plate of the hanger, said second orifice being longitudinally spaced from the connection of the truck arm with the footplate, said kingpin head being above the plate of the hanger and having flattened parallel sides under the head laterally spaced apart a distance less than the lateral dimension of the head, a removable retainer interposed between said head and the plate of the hanger, said retainer having arms spaced to pass the flattened sides of the kingpin with clearance and having upturned ends beyond the head of the kingpin, a pressure member interposed between the longitudinally extending arm of the axle bracket and the hanger, and a nut under said longitudinally extending arm in threaded engagement with the kingpin.

7. In a skate, a footplate, a hanger thereon having a plate having a flat upper surface spaced from the footplate, a roller assembly comprising an axle, an axle bracket having an arm extending longitudinally from the axle and a truck arm extending upwardly from the axle, means for connecting the upper part of the truck arm with the footplate, a kingpin passing through an orifice formed in said longitudinally extending arm of the axle bracket and having a head passing

through an orifice formed in said plate of the hanger, said second orifice being longitudinally spaced from the connection of the truck arm with the footplate, said kingpin head being above the plate of the hanger, and having a flat under surface, a flat removable retainer interposed between said head and the plate of the hanger, a resilient pressure member interposed between the longitudinally extending arm of the axle bracket and the hanger, and a nut under said longitudinally extending arm in threaded engagement with the kingpin.

8. In a skate, a footplate, a hanger thereon having a plate spaced from the footplate, a roller assembly comprising an axle, an axle bracket having an arm extending longitudinally from the axle and a truck arm extending upwardly from the axle, means for flexibly connecting the upper part of the truck arm with the footplate, a kingpin passing with clearance through an orifice formed in said longitudinally extending arm of the axle bracket and having a head passing through an orifice formed in said plate of the hanger, said second orifice being longitudinally spaced from the connection of the truck arm with the footplate, said kingpin head being above the plate of the hanger, a removable retainer interposed between said head and the plate of the hanger, an upper longitudinally elongated resilient pressure member under said plate of the hanger, a lower resilient pressure member above the longitudinally extending arm of the axle bracket, said pressure members surrounding the kingpin, a pair of independently adjustable nuts in threaded engagement with the kingpin between the pressure members, and a nut under said longitudinally extending arm in threaded engagement with the kingpin.

9. In a skate, a footplate, a hanger thereon having a plate spaced from the footplate, a roller assembly comprising an axle, an axle bracket having an arm extending longitudinally from the axle and a truck arm extending upwardly from the axle, means for flexibly connecting the upper part of the truck arm with the footplate, a kingpin passing with clearance through an orifice formed in said longitudinally extending arm of the axle bracket and having a head passing through an orifice formed in said plate of the hanger, said second orifice being longitudinally spaced from the connection of the truck arm with the footplate, said kingpin head being above

5 the plate of the hanger, a removable retainer interposed between said head and the plate of the hanger, an upper longitudinally elongated resilient pressure member under said plate of the hanger, a lower resilient pressure member above the longitudinally extending arm of the axle bracket, said pressure members surrounding the kingpin, a pair of independently adjustable nuts in threaded engagement with the kingpin between the pressure members, and a nut under said longitudinally extending arm in threaded engagement with the kingpin.

10. In a skate, a footplate, a sheet metal hanger thereon shaped to form two plates disposed at opposite angles to and spaced from the footplate and longitudinally spaced from each other, a roller assembly comprising an axle, an axle bracket having an arm extending longitudinally from the axle and a truck arm extending upwardly from the axle, means for flexibly connecting the upper part of the truck arm with one of the plates of the hanger, a kingpin passing with clearance through an orifice formed in said longitudinally extending arm of the axle bracket and having a head passing through an orifice formed in the other plate of the hanger longitudinally spaced from the connection of the truck arm with the hanger, said kingpin head being above said plate of the hanger, a removable retainer interposed between said head and said plate of the hanger, a resilient pressure member interposed between the longitudinally extending arm of the axle bracket and the hanger, and a nut under said longitudinally extending arm in threaded engagement with the kingpin.

EARL VAN HORN.
